UNITED STATES PATENT OFFICE.

CHARLES SPAETH, OF CLEVELAND, OHIO, ASSIGNOR TO THE MARVEL EQUIPMENT COMPANY, OF CLEVELAND, OHIO, A CORPORATION OF OHIO.

DISPENSING PUMP.

Application filed June 26, 1924. Serial No. 722,471.

My invention relates to an improvement in liquid dispensing pumps, particularly in a dispensing pump having a discharge spout or nozzle, and a drain pipe to catch and return the drippings or overflow to the container or source of supply. In the present case the drain pipe is an upright member adapted to swing away from the spout when a receiving vessel is thrust beneath the spout to be filled. Pint and quart measures are commonly used as receiving vessels and such measures are usually provided with hooded tops terminating in spouts to facilitate emptying the measure of its contents without spilling. The contracted or hooded top or receiving end of the vessel or measure demands correct positioning of the measure beneath the spout and constant attention on the part of the person handling the measure to avoid spilling and loss while the measure is being filled, and the measure is held in the hand in close proximity to the spout until the full quantity is delivered.

In general, my object is to provide the pump and its drain pipe with a simple device adapted to permit a receiving vessel or measure to be placed in a positive non-slipping push engagement with the drain pipe so that the measure may be used to retire the pipe and be guided at the same time to a receiving position beneath the spout and also firmly supported in an elevated position in close proximity to the spout and to permit the operator to be relieved of the weight of the measure and its contents during the entire filling operation.

In the accompanying drawings, Fig. 1 is a perspective view of a dispensing pump mounted upon a receptacle and embodying a drain pipe provided with a guide and support for a receiving vessel, a measuring vessel being also shown in a receiving position beneath the nozzle of the pump.

Fig. 2 is an enlarged top view of the pump assembly illustrated in Fig. 1.

Fig. 3 is a side elevation of a pump having a spring-controlled drain and return pipe and a guiding support or rest mounted upon the pipe which is shown in its normal drip-catching position beneath the spout. Fig. 4 is a perspective view of a drip and drain pipe and a crescent-shaped vessel-rest mounted in an adjustable position thereon.

The pump P shown in the drawings represents a known type of oil dispensing pump

adapted to be operated by a crank handle 2, and the upper end of this pump is provided with a lateral discharge spout 3 terminating in a depending delivery nozzle 4. An offset pipe 5 is seated in a vertical bore 6 at one side of base 7 of the pump, and a coiled spring 8 sleeved over the pipe within bore 6 is arranged to rotate the pipe and hold its enlarged mouth piece 9 normally beneath nozzle 4 to catch the drip and overflow which is returned to the tank or receptacle 10. The coiled spring permits the pipe to be pushed rearwardly and held temporarily in that position until a given quantity of oil is discharged into a receiving vessel or measure 11 having a handle 12 to permit it to be held in the left hand of the operator while crank handle 2 is being operated with his right hand. A hood and spout 13 on measure 11 interfere somewhat in placing the measure in the most advantageous position for the reception of the stream of oil to be delivered from the nozzle 4 while pressing and holding pipe 5 in a retired position under the tension of coiled spring 8 until the vessel is filled. To overcome this objection and to provide a centering holder and guide for the measure as well as a positive support for the measure and its contents, I sleeve a collar 14 over pipe 5, which collar is formed with a concaved or crescent-shaped branch or part 15 adapted to extend laterally beyond the side of the pipe where the round body or neck of measure 11 may be nested within the concavity and its position definitely fixed in respect to the center of turning movement of pipe 5 and so that the measure may be used to press the pipe rearwardly or away from the operator without slipping or shift in position while the measure moves in a short arc to a receiving position beneath the nozzle. When the measure is in this engaging and rest position its spout 13 extends beyond the upper vertical part of pipe 5 and may bear against the pipe to further steady and stabilize the measure, and collar 14 is rotatably mounted upon the pipe and may also be raised or lowered to different positions thereon and fixed thereto by a set screw 16. Thus, collar 14 with its bearing and rest portion 15 may be fixed on the pipe at the most advantageous distance from the nozzle to permit the hooded spout of the measures in common use to pass beneath the nozzle without interference and still be in

100
105
110

such proximity thereto that splashing or waste may be avoided in filling the measure, and the collar may be rotated to place the concaved rest and bearing portion 15 in any 5 desired radial position on the pipe to facilitate pressure engagement and assure a stable support for the measure.

What I claim, is:

1. In a dispensing device having a delivery nozzle and a drip and drain pipe pivoted to swing back and forth in respect to said nozzle, a receptacle embracing guiding and supporting yoke fixed at one side of said pipe and spaced from the top of said 10 drain pipe to permit the spout of a receiving vessel guided by said yoke to be sup-

ported on one of the prongs of the yoke without interfering of the vessel with said delivery nozzle.

2. In a dispensing pump, having a delivery nozzle and a rotatable drain pipe beneath said nozzle a vertically adjustable embracing guiding and supporting yoke and clamping means for said yoke adapted to clamp and hold said yoke in any adjusted position on said drain pipe to permit the spouts of different sized receiving vessels to be supported by said yoke without interfering with said delivery nozzle.

In testimony whereof, I affix my signature.

CHARLES SPAETH.
